UNITED STATES PATENT OFFICE.

GEORGE B. JACKSON, OF THREE RIVERS, MICHIGAN.

STAND-PIPE FOR SUPPLYING WATER TO LOCOMOTIVES.

SPECIFICATION forming part of Letters Patent No. 426,124, dated April 22, 1890.

Application filed November 29, 1889. Serial No. 331,838. (No model.)

To all whom it may concern:

Be it known that I, GEORGE B. JACKSON, a citizen of the United States, residing at Three Rivers, in the county of St. Joseph and State 5 of Michigan, have invented a new and useful Stand-Pipe for Supplying Water to Locomotives, of which the following is a specification.

This invention relates to stand-pipes for supplying water to locomotives and for other 10 purposes; and it has for its object to provide a device which shall be simple, durable, and efficient in operation.

The invention consists—

First, in constructing the stand-pipe with 15 a flexible joint, whereby normally it shall occupy a straight vertical position. When it is desired to top the pipe, the upper portion, having the spout or nozzle, may be lowered to a horizontal position.

Secondly, in an improved construction of 20 the valve, which is provided with mechanism for relieving it from excessive water-pressure, thereby enabling it to turn smoothly and freely.

Thirdly, in the arrangement of a relief-valve for protecting the pipe from the injurious effects of the water-hammer when the valve is closed.

The invention further and finally consists 25 in the improved construction and arrangement of details, which will be hereinafter fully described, and particularly pointed out in the claims.

In the drawings hereto annexed, Figure 1 30 is a front view showing the stand-pipe in a raised position. Fig. 2 is a perspective view showing the stand-pipe with its upper end lowered and in position for being tapped. Fig. 3 is a side view with dotted lines showing 35 the upper end of the stand-pipe lowered. Fig. 4 is a front view of the lower end of the stand-pipe and the valve-casing. Fig. 5 is a vertical sectional view of the main valve and valve-casing. Figs. 6 and 7 are detail views of 40 the main valve. Fig. 8 is a detail side view of the lower end of the stand-pipe. Fig. 9 is a detail view of the cylinder and piston to relieve pressure upon the main valve.

Like numerals of reference indicate like 45 parts in all the figures.

1 designates an elbow, which constitutes

the valve-casing, and which is provided with a base 2. The stand-pipe, which extends upwardly from the elbow, comprises the lower rigid portion 3 and the upper rigid portion or 55 drop-pipe 4, which is provided with a union or swiveled elbow 5, forming a discharge-nozzle. A flexible pipe 6, of suitable construction, connects the portions 3 and 4 of the stand-pipe. To the drop-pipe 4 is pivoted a hand-lever 7, for operating the valve.

The upper end of the lower portion 3 of the stand-pipe is provided with a pair of upwardly-extending rigid arms 8, to the upper ends of which are fulcrumed a pair of rigid 65 arms or levers 9, 9, extending downwardly from the drop-pipe 4. The lower ends of the levers 9, 9 are connected by rods 10, 10 with an annular weight 11, encircling the stand-pipe and serving to hold the drop-pipe normally in 70 a raised or vertical position. The fulcrum of the levers 9 being near the middle of the flexible pipe 6, the drop-pipe may readily be lowered to the approximately horizontal position shown in Fig. 2 and in dotted lines in Fig. 3 75 of the drawings.

The elbow or valve-casing 1 contains the valve, which consists of the conical or frustum-shaped members 12 and 13, the former of which forms a seat for the latter. The conical outer member 12 has at its front end a tubular stem 14, which projects through an opening 15, formed in the elbow or casing 1, where it is secured by means of a lock-nut 16. The rear end of said member has a flange 17, 80 which is tightly seated in a recess 18, provided for its reception in the open end of the casing, which is in turn connected with the water-main 19. The inner valve member or spigot 13 consists of a conical shell fitted in 85 the outer member or seat 12, and having a stem 20 at its small end, which projects through the tubular stem 14, which is provided with a stuffing-nut 21 to make a tight joint. The seat 12 and spigot 13 have ports 22, 23, which 90 are adapted to register with each other, and which may be opened or closed by a quarter-turn. These ports are triangular in shape, as will be seen in Figs. 6 and 7. By this construction the ports, when opened, will admit the 95 water rapidly, while in shutting off the water will be shut off gradually, thereby avoiding 100

excessive strain which is apt to result from the accumulated pressure of the water when shut off too suddenly.

24 is an angular or L-shaped passage extending through the stem 20 of the spigot and terminating in that portion of the wall of the spigot which, when the valve is closed, as in Fig. 5, registers with the uppermost port 22 in the seat, which communicates with the stand-pipe. The channel 24, it will be seen, thus serves as a drain for the latter and effectually prevents water from remaining and stagnating or freezing therein.

The valve - stem 20 is provided with a weighted lever 25, to which is connected a rod 26, and a rod 27 is connected with the upper end of rod 26. A similar rod 27^a is connected to the hand-lever 7, which is pivoted to the drop-pipe 4, and the ends of the rods 27 27^a are connected by a chain 28, passing over sheaves 29, journaled to the inner side of one of the upright arms 8. It will thus be seen that when the drop-pipe is lowered and within reach the valve may be readily opened by operating the hand-lever 7, the weighted lever 25 serving to close it automatically when the hand-lever is released.

For the purpose of relieving the force with which the spigot or valve member 13 is held to its seat by the pressure of the water in the main and the difficulty in turning the valve resulting therefrom, I avail myself of mechanism as follows: Upon the outer ends of a series of bolts 30 30, extending laterally from the valve-casing parallel to and around the stem of the valve, I secure a block or plate 31, having a short cylindrical bore 32 concentric with the valve-stem, and in which is fitted a piston 33, having a stem 34, the inner end of which bears against the valve-stem, and is provided with an angular channel 35, registering with the channel 24 in the latter. Upon the bolts 30 at the outer end of the cylinder 31 is secured a head 36, having in its inner side a recess 37 and provided with an opening 38, which is connected by a small pipe 39 with the water-main 19. It follows that the water from the latter will enter the recess 37 and the bore 32 in the cylinder and force the piston 33 in the direction of and against the valve-stem with a force equal to that exercised by the water against the inner or rear side of the valve member or piston 13. By properly gaging the area of the piston 33 it will thus be seen that the valve may be balanced as nearly as may be desired, thus reducing the force required to turn it in its seat very considerably.

In a valve of the dimensions necessary for a railroad stand-pipe the water hammer or blow caused by the cumulative increase of pressure when the flow is suddenly cut off is very considerable and severely injurious both to the valve and pipes. For the purpose of reducing or doing away with the effects thereof, I connect the main with the stand-pipe by an elbow-pipe 40, in which is located a valve 41, which is normally held closed by the ac-

tion of a spring 42, the pressure of which is somewhat greater than the normal pressure of the water in the main. It will be seen that when the water is cut off suddenly the cumulative energy of pressure will be exerted against the spring 42, thus opening the valve 41 and permitting water to flow through the pipe 40 into the stand-pipe. As soon as the increased pressure ceases the valve 41 is returned to its seat by the action of the spring. By this device excessive strain upon and injury to the walls of the pipes are effectually avoided.

The operation and advantages of my invention will be readily understood from the foregoing description, taken in connection with the drawings hereto annexed, by those skilled in the art to which it appertains. The construction of the stand-pipe is comparatively simple and inexpensive, and the drop-pipe when not in use is sure to be out of the way and in a position where it can interfere with or be interfered with by nothing. The lower portion of the stand-pipe and the valve-casing is to be inclosed and protected in some suitable manner, which it is not deemed necessary to describe in detail. The valve mechanism is simple, easily operated, and not liable to get out of order. An important advantage of the invention is that the flexible connecting-pipe carrying the discharge-nozzle may be lowered to either side, while the union-elbow which forms the discharge-nozzle may be turned so as to discharge the water downwardly on either side. The stand-pipe may therefore be arranged between two railroad-tracks and used for supplying water to engines on either track.

Having thus described my invention, I claim and desire to secure by Letters Patent of the United States—

1. In a stand-pipe, the combination of a lower rigid pipe-section, a rigid drop-pipe having a swiveled or union elbow, a flexible connecting-pipe, and pivoted connecting-arms attached rigidly to the lower section and to the drop-pipe, respectively, substantially as set forth.

2. The combination of the stand-pipe having upwardly-extending rigid arms, the drop-pipe having downwardly-extending levers fulcrumed to said arms, the flexible connecting-pipe, and a weight connected to the levers, substantially as set forth.

3. The combination, with the stand-pipe, the flexible connecting-pipe, and the drop-pipe, of an annular weight surrounding and sliding vertically upon the stand-pipe, the arms extending upwardly from the latter, the levers extending downwardly from the drop-pipe and fulcrumed to said arms, and the rod connecting said levers with the annular weight, substantially as set forth.

4. The combination of the elbow or valve-casing connected with the main, the stand-pipe mounted upon said casing, the valve, the weighted lever secured upon the valve-stem,

the flexible connecting-pipe, the drop-pipe, the pivotally-connected arms and levers, the sheave mounted upon one of said arms, a hand-lever pivoted upon the drop-pipe, the 5 rods connected to said hand-lever and to the lever upon the valve-stem, and a chain connecting said rods and passing over the sheave, substantially as set forth.

5. The combination of the elbow or casing, 10 the conical shell or seat having tubular stem 14, the lock-nut, the conical shell or spigot having the stem 20 extending through the tubular stem 14, and the stuffing-nut, substantially as set forth.

15 6. The combination of the elbow or casing, the stand-pipe, the conical shell or valve-seat having tubular stem, and the conical shell or spigot having a stem extending through said tubular stem and provided with a draining- 20 channel, the inner end of which, when the valve is closed, registers with a port in the valve-seat communicating with the stand- pipe, substantially as set forth.

7. The combination of the elbow or casing, 25 the conical shell or valve-seat mounted therein and having projecting tubular stem, the valve or spigot having a stem extending through the tubular stem of the seat, a cylinder bolted to the elbow or casing, a piston 30 mounted in said cylinder and pressing against the outer end of the valve-stem, and a pipe connecting the cylinder-head with the water-main which is connected to the elbow or valve- casing, substantially as set forth.

8. The combination, with the valve having 35 a projecting stem provided with a drain-channel, of the piston arranged to press against the outer end of the valve-stem, and having an opening or passage registering with said drain-channel, substantially as set forth. 40

9. The combination of the elbow or casing, the conical valve-seat mounted therein and having projecting tubular stem, the valve having the stem extending through said tubular stem and provided with a drain- 45 channel, the cylinder and head connected to the elbow or casing by bolts arranged around the valve-stem, the piston pressing against the latter and having an opening registering with the outlet of the drain-channel therein, 50 a pipe connecting the cylinder-head with the main or water supply, and the operating-lever mounted upon the valve-stem and extending between the connecting-bolts, substantially as set forth. 55

10. The combination of the valve having the projecting stem, the cylinder, the piston, the cylinder-head 36, having recess 37, and a pipe connecting said cylinder-head with the water-main, substantially as set forth. 60

In testimony that I claim the foregoing as my own I have hereto affixed my signature in presence of two witnesses.

GEORGE B. JACKSON.
